DESIGN FOR A CASING FOR WATER HEATERS AND THE LIKE

Henry W. A. Johnson, Roslindale, Boston, and
Robert H. Moore, Lexington, Mass.

Application September 20, 1934, Serial No. 53,340

Term of patent 14 years

To all whom it may concern:

Be it known that we, HENRY W. A. JOHNSON and ROBERT H. MOORE, citizens of the United States, residing at Roslindale, Boston, and Lexington, respectively, in the counties of Suffolk and Middlesex, respectively, and State of Massachusetts, have invented a new, original, and ornamental Design for a Casing for Water Heaters and the like, of which the following is a specification, reference being had to the accompanying drawings, forming part thereof:

Fig. 1 is a side elevational view of a water heating casing showing our new design, and

Fig. 2 is a sectional view on the line 2—2 of Fig. 1.

We claim:

The ornamental design for a casing for water heaters and the like, substantially as shown.

HENRY W. A. JOHNSON.
ROBERT H. MOORE.
